Primary Examiner — David Muller*Assistant Examiner* — Nathan Johnston(74) *Attorney, Agent, or Firm* — Young & Thompson(57) **CLAIM**

The ornamental design for a duct member for coolant and chip extraction, as shown and described.

DESCRIPTION

FIG. 1 is a top, right side, and rear perspective view of a chip and coolant extraction duct member showing the new design;

FIG. 2 is rear elevation view thereof;

FIG. 3 is a top plan view thereof;

FIG. 4 is a bottom plan view thereof; and,

FIG. 5 is a left side elevation view thereof.

The duct member for coolant and chip extraction is symmetrical and the sides appear the same.
